CATHODE-RAY TUBE

John M. Cage, Montclair, N. J., assignor to Cage Projects, Inc., Union City, N. J., a corporation of New Jersey

Application August 28, 1948, Serial No. 46,585

7 Claims. (Cl. 313—85)

1

This invention relates to image reproducing tubes and more particularly concerns a new and improved image reproducing tube for television and other similar applications.

One object of the invention is a new and improved reproducing tube of the character set forth whereby increased brightness and definition and greatly improved stability and life are obtained.

Another object of the invention is an improved image reproducing tube particularly useful in the projection of televised and other images.

Another object is a new and improved electron beam accelerating structure for reproducing tubes.

Another object is a new and improved method and means for shielding the electron beam of cathode ray tubes and to prevent the accumulation of free electrons on the tube walls.

Still another object is an improved cathode ray tube for the reproduction of images.

Another object is an improved shield or screen structure for cathode ray tubes.

Other objects of the invention will hereinafter appear.

For a better understanding of the invention reference is made to the following description and accompanying drawings forming a part of this application.

In the drawings—

Fig. 1 is a somewhat diagrammatic view illustrating one embodiment of the invention;

Fig. 2 is a cross-sectional view of Fig. 1 taken along the lines 2, 2 thereof;

Fig. 3 is another embodiment of the invention;

Fig. 4 is a cross-sectional view taken along the lines 4, 4 of Fig. 3;

Fig. 5 illustrates still another embodiment of the invention;

Fig. 6 is a cross-section of the embodiment shown in Fig. 5 along the lines 6, 6 thereof;

Figs. 7 and 8 are cross-sectional views of still another embodiment of the invention;

Fig. 9 is a cross-section of a cathode ray tube embodying one form of the invention;

Figs. 10 and 11 illustrate still another form of the invention;

Figs. 12 and 13 illustrate still another form of the invention; and

Fig. 14 is a section along the line 14, 14 of Fig. 13.

In conventional image reproducing tubes the accumulation of free electrons on the tube walls is prevented by coating the inside of the glass tube throughout the portion of the tube where

such shielding is desired. For example, in the conventional image reproducing tubes for television this coating in the form of colloidal graphite or carbon is applied to the cylindrical part of the tube at a point between the front end of the electron gun and the image reproducing screen.

The use of such a colloidal graphite or carbon solution as a coating for the conventional tubes is not entirely satisfactory. For instance, the higher the accelerating voltages used the greater the tendency of the carbon or graphite to contaminate the vacuum within the tube and materially impair the operation thereof. Moreover, the application of the shield directly to the glass

tubing tends to limit the accelerating voltage which may be used due to the insulating problems, and the coating of the interior of the tube is a comparatively expensive operation. By means of my invention I avoid these and other objections to the disadvantages of the conventional tube structures.

In Fig. 1 I have shown somewhat diagrammatically a tube wherein contaminating coatings are dispensed with while at the same time the beam can be adequately and completely shielded and the accumulation of free electrons prevented. This enables the use of very much higher voltages on image reproducing tubes and produces a tube that is more dependable and that will have a very much longer life. In the figure, 10 denotes the cylindrical section of the glass envelope, and 12 a portion of the conical section thereof. In the lefthand end of the cylindrical section 10 the filament and cathode structure are denoted by the numeral 14, the control grid or grids are denoted by the numeral 16 following the cathode and the next successive element is the second or high voltage electron beam accelerating anode 18.

To shield the electron beam as it leaves the second anode 18, I have provided a plurality of rod or wire-like members 20 surrounding the beam and spaced from the cylindrical section 10. These rod-like members 20 are substantially uniformly spaced one from the other and are connected together at one end by means of a suitable metallic ring 22 which also acts as the mechanical support for the individual rods or wires 20.

This structure can be supported centrally within the tube 10 by any suitable means and may in turn also be arranged to support the second anode 18. This may be advisable under certain conditions wherein it is desired to maintain both the shield and the second anode at the same high potential.

In cathode ray tubes embodying the magnetic

deflection coils my new and improved shield for the cathode ray beam is particularly effective since the coils usually surround the tube at a point after the second anode 18 and the magnetic fields must pass through the shield. With my shield I have been able to reduce both eddy and circulating currents to a minimum and by making the rod-like members of a non-magnetic metallic material I have found that I can obtain excellent beam control characteristics of the tube with little or no undue load on the deflecting coil. As a matter of fact I have found that my new and improved shield has little or no effect on the power consumed by the surrounding magnetic deflection and focusing coils, while at the same time it effectively shields the cathode ray beam and prevents the collection of free electrons during the operation of the tube and will not in any way contaminate the vacuum therein. If desired, the surface of the shield can be blackened and the tube coated on the outside thereof to reduce reflection of light onto the image reproducing screen.

In Fig. 3 I have illustrated an embodiment of the invention wherein the shield or screen is formed integrally with the second anode element 18. In this figure, 10 denotes the cylindrical section of the tube and 12 denotes the conical section. At the left of the tube is again illustrated the cathode 14 having a filament 14' therein, a control grid or first anode 16 and a suitable insulating support 24 and insulating rods 26 for supporting the elements 14 and 16 in proper alignment. The shield consists of a plurality of spaced metallic wires 28 preferably of a non-magnetic material such as Monel or the like, although under certain conditions magnetic materials would be satisfactory. These wires are curved inwardly toward the second anode 18 and are fastened thereto by welding or other suitable means. The righthand section of the wires 28 is curved outwardly as they pass the junction between the cylindrical and conical sections of the tube envelope, so that the end portions of the wires will not interfere with the picture in any way. The second anode 18 together with the shielding wires 28 are supported in proper position within the tube by an inner cylinder 30 of insulating material having flanges 30' on each of its ends for fastening it in position within the tube 10. Each of the wires 28 is curved outwardly from the second anode 18 to meet the inner surface of the glass sleeve 30, whereupon it extends longitudinally along the surface 30 to the end thereof and is then curved outwardly as indicated at 28'. To rigidly support the wires in their spaced position, each wire 28 may be embedded in the glass sleeve 30 substantially as shown at 32 in Fig. 4. Surrounding the cylindrical tube part 10 are coils 34 and 36 for focusing and deflecting the electron beam as it leaves the accelerating anode 18 through the orifice 18' therein.

The deflecting coil 36 generates two alternating magnetic fields so that the electron beam will scan the screen in the tube in both horizontal and vertical directions. If a large body of metal or other conducting material of low resistance is placed in the center of the coil, large circulating and eddy currents will be induced therein. I have avoided the generation of these currents by shielding the beam with an electrically conductive shield having a plurality of spaced wires connected at only one end so that circulating currents are completely eliminated and eddy cur-

rents are reduced to an insignificant amount. Moreover, I have actually found that by using a plurality of spaced wires in the manner illustrated a uniform electrostatic field is produced about the beam to collect free electrons and there is no indication whatsoever in the resultant picture to indicate in any way that the shielding has been accomplished in this manner.

Although I have illustrated in Figs. 1-4 wire or rod-like metallic members spaced about the beam and extending longitudinally thereof, each wire could of course be in the form of a helix, or the shield could comprise a screen formed by weaving individual strands of wire in such a manner as to prevent the generation of circulating currents that would place an undesirable load on the deflecting coils. In Figs. 7 and 8 I have shown a modification of the structure illustrated in Fig. 3 wherein the wires 28 have been replaced by deposits of silver, palladium or other suitable material in a plurality of grooves 38 formed in the inner surface of the glass sleeve 30'. The silver or palladium can be deposited in the grooves 38 by coating the inner grooved surface 25 of the sleeve by electro-deposition or other suitable process and then removing the silver from the surfaces 40 between the grooves 38. With the silver deposited in the grooves 38, the second anode 18 having a plurality of short outwardly 30 extending spring-like fingers 42 would then be placed in the sleeve with each finger resting in one of the grooves 38 to contact the silver strips and connect them together.

An alternative arrangement is shown in Figs. 35 5 and 6 wherein I have illustrated the glass sleeve 30' fastened in the tube part 10 as previously described in connection with the sleeve 30 in Fig. 3. In this adaptation the shield comprises an extremely thin layer 46 of platinum bright, palladium or other metallic coating having a resistance of preferably at least 150-200 ohms per square inch. The material of which the surface 46 is formed should be of a non-evaporatable material when used under normal voltages and temperatures experienced in the operation of cathode ray tubes so that it will not contaminate the tube 45 in any way.

By embodying the insulating sleeve structure within the cylindrical tube part 10 as illustrated in this and other figures, I am able to apply extremely high voltages to the tube without the danger of puncturing the tube should a relatively low potential or grounded surface be brought into close proximity with the outer part of the tube envelope. This structure also effectively shields the tube beam and will not result in contamination of the tube with the application of high voltages thereto.

Moreover, with the structure I have been able 60 to apply accelerating potentials to the tube of the order of 50,000 to 75,000 volts and even higher without damaging the envelope 10, 12 in any way.

In the embodiment shown in Fig. 5 the second anode 18 can be supported by the glass sleeve 30' in any suitable manner as by a number of springs 44 fastened to the anode and extending outwardly to bear against the metallized and non-evaporatable surface 46 of the inside of the sleeve 30.

Fig. 6 is a cross-sectional view of the form of the invention of Fig. 5 and illustrates the spacing obtained between the outer surface of the tube envelope part 10 and the inner shielding 75 layer 46. The gap between the concentric cylin-

cylindrical portions 35 and 10 is of course evacuated along with the evacuation of the tube as a whole and provides a high degree of insulation to prevent arc-over and irreparable damage to the tube.

Another important advantage of the structures heretofore described is realized particularly in humid weather. Normally a projection type ray tube, for instance, is completely enclosed in a cabinet and its temperature is therefore at a fairly low value with reference to the ambient temperature during times when the set is not operating. Under such conditions a thin film of moisture may condense on the outer surface of the tube and in the presence of dirt and dust which usually also settles on the tube a fairly good conductive layer to ground will be formed. If the potential on the shield, which is conventionally disposed on the inner wall of the tube part 10, exceeds the normal dielectric strength of the glass, the tube wall will be punctured. This is a very definite limitation on the capacity of cathode ray tubes. With my invention, however, I can materially increase the potential to be applied to the shield without danger of breakdown and I can moreover avoid contamination of the tube by reason of the particular character of the shielding structure and, in addition, eliminate for all practical purposes circulating and eddy currents which produce an undue load on the deflection coil.

In Fig. 9 I have illustrated an alternate embodiment of the invention. This embodiment is somewhat similar to the embodiment shown in Fig. 3 in that a plurality of individual wires or rods 28 are fastened at one end to the second anode 18 and extend longitudinally of the tube. In this embodiment an internal tubular glass sleeve 50 is supported at the lefthand end at the base 10' of the tube 10, and is provided at its other end with a slightly flanged section 52 which curves outwardly to contact the inner surface of the cylindrical tube part 10 at the point where it begins to taper outwardly to form the conical or flared section 12. In this embodiment the wires or rods terminate within the flanged section 12 and are flared outwardly so that the ends of the wires will not interfere with the electron beam at the edges of the picture to be formed on the screen of the tube. The wires 28 may be embedded in the glass tube 50 as previously set forth, or they may just rest against the inner surface thereof and be held in place by frictional contact. It would also be possible to use a structure such as shown, for instance, in Fig. 7 wherein the small grooves 38 may be used to retain the wires 28 in properly spaced alignment about the inner surface thereof.

Still another method of forming my new and improved tube structure which I have found to be particularly satisfactory is illustrated in Figs. 10 and 11 wherein the cathode ray tube is formed of a cylindrical section 10, as previously described, which terminates in a flared section 12 curving outwardly to form a bell-like part which is closed at its larger end to provide a surface for receiving and holding the fluorescent screen on which the picture is formed. In this embodiment a circular glass sleeve 54 is flared outwardly either side of a point substantially in line with the front or righthand end of the anode 18. The wires 56 which are uniformly spaced about the electron beam and act to shield the electron beam, as previously described, are each fastened at their inner ends to the anode 18 and curved outwardly therefrom to form, in their position of rest, a cone with the base part being three or four times

the diameter of the glass tube 54. The front end of the anode 18 is provided with a flange 58 surrounding the anode and through which the several wires 56 are passed. The flange 58, however, is slightly larger than the narrowest section of the tube 54 so that when the anode 18 is inserted from the lefthand end the flange 58 will contact the internal wall of the tube 54 to limit any further forward movement. Since the wires 56 are flared outwardly in their position of rest, they will, upon being compressed for insertion into the tube 54, expand to frictionally contact the inner wall of the front portion 54' of the glass tubular part 54 and tend in effect to pull the flange 58 forwardly to securely engage it with the internal wall of the sleeve 54. This structure provides a completely self-supporting structure for the second anode together with the shielding wires 56. The tube 54 may be held in position within the tube envelope part 10 either by welding the sleeve 54 in position in the tube 10, or by providing suitable flanges or projections on the inside of the tube part 10 to limit the longitudinal movement of the inner sleeve or tube 54.

This particular structure therefore provides a simple and effective method for holding the second anode and shield in place and providing a relatively long leakage path inside the tube to prevent arc-over to the other controlled electrodes as well as to prevent breakdown through the tube walls due to the close proximity of a ground to the tube wall or the formation of a conductive path along the wall to a grounded point on the tube or the apparatus with which it may be associated.

With this new and improved gun structure and more particularly the new and improved shield and mounting therefor, a more dependable and stable tube is provided that is capable of producing a very much improved picture.

In each of the previous embodiments I have illustrated the shield as terminating at just inside the flange section 12 of the tube and curved outwardly slightly so that it will not interfere with the normal excursions of the beam within the tube. This structure, however, particularly provides, in another aspect, other important advantages which result in further improvement in the cathode ray tube.

In conventional tubes to my knowledge the fluorescent screen is normally disposed on the closed end 12' of the flared section 12 of the tube and because of certain structural requirements the front end of the tube 12' must necessarily be curved outwardly slightly. The formation of a picture on this curved surface produces some degree of distortion together with the fact that dirt, finger marks and other smudges on the outer part of the tube front 12' will tend to impair or obliterate the projected image to some extent. This is particularly noticeable in projection, since both the inner and outer surfaces of the front wall are substantially in focus. Moreover, since the screen is not flat it is sometimes necessary to stop the lens down to some extent to increase the depth of focus so that all parts of the picture will be focused on the screen. Further distortion is also encountered because of the projection of a curved picture onto a flat screen.

In Fig. 12 I have illustrated a structure in accordance with the invention whereby these disadvantages are overcome and at the same time I am able to completely shield the beam from the

second anode part 18 to the screen upon which the picture is reproduced. The screen 60 is preferably made with an outer layer of quartz or other similar material 62. On the inner surface of the quartz or Pyrex layer is a layer of phosphor or phosphorescent material 64 which is then covered by a deposit of aluminum 65. Surrounding the screen 60, which is preferably circular in shape, is a glass ring 66 having a plurality of openings 67 extending therethrough at spaced intervals. A view of this ring 66 is shown in Fig. 14 having the radially spaced openings 67. In this embodiment I have shown a plurality of longitudinally disposed wires 68 extending from the cylindrical section 10 of the tube to the ring 66 with the front or screen ends of the wires 68 being secured in the ring openings 67. The wires 68 in this particular embodiment constitute in effect extensions of the wires or rods 28 in Fig. 1 or the wires or rods 28 in Figs. 3, 9 and 10. The wires 68, therefore, are in effect connected together at the second anode while being insulated at the screen part by the glass or quartz ring 66. The high voltage connection for energizing the second anode and the shield wires 68 is made through the connection 70 and the lead 71 to only one of the wires 68. The screen can be similarly polarized by a short connection 72 from the aluminum layer 65 of the screen to one of the wires 68. A substantially rigid support can be provided for the screen 60 and the surrounding glass ring 66 by providing a plurality of spaced brackets or springs 74 extending outwardly from the ring 66 to contact the inner surface of the glass envelope 12. In the case of very high potentials, the ring 66 itself can be increased in width so as to extend outwardly and even directly contact and be welded to the glass envelope 12.

Fig. 13 is another embodiment of the invention along the lines of that illustrated in Fig. 12. In this embodiment, however, I have illustrated a structure whereby I can get potential gradations between the screen 60 and the second anode 18 as shown, for instance, in Fig. 3. In this embodiment the wires 28 are illustrated as terminating just inside the flared section of the tube 12 and each of the wires is provided with an insulator 80 on its end. A second wire 82 extends from the other side of the insulator 20 and it too terminates at a point approximately midway between the insulator 80 and the screen 60. A second insulator 84 is secured to the end of the wire 82 and supports a third wire 86 which extends to and aids in the support of the screen 60. In this particular adaptation the ring 66 surrounding the screen is preferably of a conductive nature so that each of the wires 86 will in effect be connected together so that they will all be at a uniform potential. Similarly, a series of jumpers 88 are provided between the wires 82 so that each of these wires can also be maintained at the same potential.

With this arrangement I apply the high voltage potential to the contact 70 extending through the wall 12 of the tube which in turn is connected to the wires 86 by a lead 71. A high resistance 90 is connected between the lead 71 and one of the wires 82. A second resistance 92 is connected between one of the wires 82 and one of the wires 28. The side of the resistor 92 connected with one of the wires 28 is also connected with the terminal 94 extending through the glass and in turn connected to ground 96 through a resistor 98. In this way a voltage divider system is provided so that if for instance

100,000 volts are applied at the contact 70 each of the wires 86 together with the screen 60 will be at that potential. The resistors 90, 92 and 98 may then be proportioned, for example, so that the potential on the wires 82 will be, say, 75,000 volts and the potential applied to the wires 28 and the second anode 18 will be about 50,000 volts. The advantages of the employment of a high voltage on the screen to get added beam acceleration, and, therefore, increased brightness and definition of the image, will be realized while at the same time a materially lower voltage will actually be applied to the second anode so that a greater degree of safety and dependability will be realized when using these extremely high potentials.

In the form of the invention shown in Fig. 13 I prefer to form glass spacers 100 within the tube part 12 and interpose suitable springs 102 between the inner ends of the spacers and the outer edge of the ring 66 to firmly support the screen centrally of the conical section of the tube.

By mounting the screen in this manner a materially improved picture is obtained and at the same time better high voltage insulation is provided. Since the front end of the tube is not in focus when the picture is projected, dirt, smudges, imperfections in the glass will not appear with objectionable clarity on the screen and no distortion will be encountered through the formation of a curved picture for projection on the screen.

I claim:

1. In a cathode ray tube a gun structure enclosed within the evacuated tube envelope comprising means for generating an electron beam, means for controlling and focusing the beam and a second anode for accelerating the beam including a plurality of individual elongated conductive elements extending from said anode in the direction of movement of the beam.

2. In a cathode ray tube, a gun structure enclosed within the evacuated tube envelope comprising means for generating an electron beam, means for controlling and focusing the beam and a second anode for accelerating the beam including a plurality of wire-like elements extending from the anode in the direction of movement of the beam, said elements being spaced about the beam and connected one to the other and to the second anode.

3. In a cathode ray tube according to claim 2 wherein said elements are electrically connected together at the second anode and are spaced substantially uniformly about the beam.

4. In an image reproducing tube, an anode for accelerating the electron beam and a plurality of spaced elements each extending from the anode in the direction of movement of the beam, said elements surrounding and providing an electrostatic shield for the beam.

5. In a cathode ray tube wherein the beam is magnetically deflected, means for shielding the electron beam between the accelerating anode and the screen comprising a plurality of spaced conductors surrounding the beam and connected together at a point removed from the point of deflection of the beam to form a unipotential shield.

6. In a cathode ray tube wherein the beam is magnetically deflected, means for shielding the electron beam between the accelerating anode and the screen comprising a plurality of spaced conductors surrounding the beam and connected together at a point removed from the point of deflection of the beam, said conductors being in the

form of thin rods connected together at the accelerating anode end thereof.

7. An image reproducing tube comprising a cathode for generating an electron beam, controlling means for said beam including an accelerating anode, a screen for intercepting said beam, and means for shielding said beam comprising a tubular insulator having flared end portions adapted to contact and be held in position between the anode and the screen by the reproducing tube wall, and a plurality of wires each fastened at one end to the anode and extending in spaced relation one to the other through the insulator and bearing firmly against the wall thereof, and means for connecting a high accelerating potential to the anode.

JOHN M. CAGE.
